CARBURETOR

Warren C. Conover, Waukegan, Ill., assignor to
Outboard, Marine & Manufacturing Company,
Waukegan, Ill., a corporation of Delaware

Application August 1, 1940, Serial No. 349,078

9 Claims. (Cl. 123—119)

This invention relates to improvements in carburetors with particular reference to the type of carburetor in which carbureted air is supplied to a dual manifold arrangement.

It is the primary object of the invention to provide novel and improved means whereby the mixture will be uniform in each of two manifolds supplied with carbureted air. Both in four cycle engine practice and in two cycle engine practice, it is frequently desirable to employ separate manifolds for different cylinders or groups of cylinders. If the mixture supplied to one manifold is richer than that supplied to another, or varies in quantity, the cylinders will fire unevenly. Where each manifold is supplied with a separate carburetor, it is almost impossible to secure uniformity of mixture. The same is true where the output of a single carburetor is divided, after carburetion, between the manifolds.

By the present invention, I seek to provide a very simple, inexpensive and direct way of equalizing the carburetion as between a plurality of manifolds supplied by a single jet. It is a further object of the invention to provide an arrangement whereby portions of the manifolds are formed in a throttle valve structure, preferably directly associated with the jet.

Other objects of the invention will be apparent from the following disclosure.

In the drawing:

Fig. 1 is a view partially in plan and partially in horizontal section showing a carburetor embodying the invention.

Fig. 2 is a view partially in side elevation and partially in vertical section through the carburetor and associated structure shown in Fig. 1.

Like parts are identified by the same reference characters throughout the several views.

By way of illustration, my improved carburetor is shown applied to a dual crank case rotary valve two cycle engine, this being one structure in which dual manifolding is desired. The crank shaft 3 is provided with cranks 4 and 5 in the crank cases 6 and 7. The crank shaft cheeks 8 and 9 constitute rotary valves having segmental openings such as those indicated at 10 and 11 for admitting to the respective crank cases combustible mixture supplied through the manifold passages 12 and 13, respectively. Manifold passage 12 turns upwardly to be controlled by valve numbered 8 while manifold passage 13 turns downwardly to be controlled by valve numbered 9.

As viewed in Fig. 1, the passages 12 and 13 in

the crank case structure are horizontal and at the same level.

The carbureting chamber 15 is provided in a lateral extension with the conventional float chamber 16, details of which are not shown. It has an air inlet port at 17 and is provided at 18 with a cylindrical bearing in which the throttle valve 19 is rotatable. The throttle valve 19 comprises a generally cylindrical structure having an air passage divided by partition 20 to comprise separate manifolds 21 and 22 of gradually increasing cross section. These manifolds communicate with the divergent manifold passages 23 and 24 which lead respectively into the crank case manifold passages 12 and 13.

The diverging manifold passage sections 23 and 24 are spaced by a partition 25 which is in line with partition 20 in the throttle valve, but is spaced therefrom. In the space 26, which affords communication between the separate manifold branches, is the carburetor jet 27 which projects on a minor chord into the cylindrical space in which the throttle valve rotates. This jet is supplied with fuel from the float chamber 16 through a series of ports and passages subject to the control of needle valve 28. The cross sectional areas of the manifold sections 23 and 24 are equal as are the cross sectional areas of manifold sections 12 and 13. The cross sectional areas of manifold branches 21 and 22 within the throttle valve 19 are equal to each other, but are preferably somewhat reduced as compared with the areas of the extensions 23 and 24 thereof.

While I have shown portions of the manifold branches formed in a throttle valve, I wish to make it clear that in the broader aspects of the present invention, it is immaterial whether these passage sections be formed in a throttle valve or in some other portion of the carbureting chamber. Broadly, it is only important that the air is carried by separate manifold passages which communicate with each other about the jet. In addition to this broad principle, it is, of course, advantageous in the interests of compactness and simplicity to incorporate portions of the passages in the throttle valve as shown.

The throttle valve is held in place by a closure 30 through which the valve stem projects at 31 to be manually adjusted by a handle 32. Naturally, the manner in which the throttle valve is controlled is not of importance to the present invention.

Since the engine disclosed is a two cycle en-

gine, it will be understood that the mixture delivered to the respective crank cases 6 and 7 will be compressed therein and transferred to the respective cylinders 33 and 34. For the purposes of the present invention, it is immaterial whether the mixture is delivered directly to the cylinder, as in four cycle engine practice, or is first delivered to the respective crank cases, as in the two cycle engine disclosed.

In either case, the uniformity of mixture supplied through the separate manifold passage will be surprisingly constant and more nearly identical as between the separate manifolds than in any other construction which is known to me. This is particularly true in the device as disclosed where the respective cylinders are drawing their mixture alternately through the carburetor. When mixture is being drawn into crank case 6 through manifold passage 12, no mixture is passing through manifold passage 13 to crank case 7.

Under these circumstances, it will be apparent that the major portion of the air entering manifold passage 12 will come directly thereto through the manifold section 21, but a part of the air supplied to such passage will come to the passage through manifold section 22 and the communication aperture 26 which affords communication between the passages. In so doing, the portion of the air traversing the by-pass opening will be carbureted and the jet 27 and needle valve 28 are so devised that sufficient carburetion will be supplied to this portion of the air to satisfy the entire requirements of the cylinder to which this portion of the air is supplied.

Conversely, when cylinder 34 and crank case 7 are drawing air through manifold passages 13 and 24, the major portion of such air will be supplied through manifold section 22, but a portion thereof will cross over from manifold section 21 through the communication opening 26 and will be carbureted in passing the jet 27. I believe that superior results are possible if the air stream is divided, as by partition 20, before it encounters the jet at 27, but in any event there should be some definite exchange of air from one side of the manifold system to the other across the jet. It is this exchange which is believed to account for the surprising uniformity of carburetion in both branches of the manifold system.

I claim:

1. A carburetor of the character described comprising the combination with a carbureting chamber having separate passages and intervening partition and a cylindrical throttle valve bearing from which said passages open, of a jet nozzle disposed on a minor chord of said bearing between said passages and substantially in line with said partition, and a throttle valve rotatable in said bearing and provided with transverse passage sections opening directly toward the respective passages and an intervening partition substantially aligned with said jet nozzle and said first mentioned partition, said jet nozzle being spaced between said partitions.

2. A carburetor having separate air passages opening in proximity to each other and communicating with each other at a point intermediate the length of each, a single fuel jet nozzle disposed at said point of communication in a position to carburet at least a part of the air entering each, and means for supplying liquid fuel to said nozzle, variations in suction in the respective passages being thereby adapted to draw

air from one of the passages into the other across the jet nozzle.

3. A carburetor for internal combustion engines having separate manifold inlets and means for alternately applying suction at the respective inlets, said carburetor having separate passages leading to the respective manifold inlets and cross connected for delivery of the air streams to either of such inlets, and said carburetor having its main fuel jet nozzle disposed in said cross connection in a position to be exposed to suction exerted through either of the manifold inlets.

4. A carburetor comprising a chamber having inlet and outlet portions and an intermediate partition, a nozzle connected with a source of liquid fuel supply and located in line with and adjacent the inner end of said partition, and another partition located between said nozzle and the chamber inlet substantially in the plane of the first mentioned partition, whereby air passing from one side of the chamber to the other may be concentrated upon the nozzle outlet for aspirating purposes.

5. A carburetor, comprising a chamber of a generally tubular form and provided with inlet and outlet ports, a cylindrical throttle valve transversely disposed with its ends journaled in the side walls of the chamber and intermediately ported for communication between the inlet and outlet portions of the chamber, a partition in the throttle valve port adapted to sub-divide the air stream passing therethrough, means for correspondingly sub-dividing the air stream at the carburetor outlet, and a fuel nozzle extending into the outlet end of the throttle valve port in the plane of its partition and spaced therefrom.

6. In a carburetor of the character described, the combination with means providing separate outlet passages of substantially uniform cross section and corresponding air inlet passages also of like cross section with reference to each other, the cross sections of the respective inlet passages being reduced as compared with those of the outlet passages, said carburetor having a mixing chamber between the inlet and outlet passages permitting air flow from either inlet passage to either outlet passage, and a main fuel nozzle located in the central portion of the mixing chamber substantially in a plane midway between the outlet passages, whereby air may be drawn by suction applied to either outlet passage across the nozzle from the opposite side of the mixing chamber.

7. A carburetor having a generally tubular air passage expanded at its inner end to cover the inlet ports of a duplex manifold, a cylindrical throttle valve journaled in the walls of the passage and ported for air delivery therethrough, a partition in the throttle valve port disposed in a plane which includes the axis of said passage and located in front of the outlet end of said port, and a fuel nozzle extending through the wall of the passage and projecting on a minor chord into the throttle valve port, with its outlet in line with the partition, said partition being adapted to sub-divide the air stream flowing through said port, and the walls of said passage being formed to provide a cross connection between the air streams on opposite sides of said partition, and also adapted to concentrate upon said nozzle air flowing through said cross connection.

8. The combination with an internal combustion engine having dual inlet passages and means for applying suction alternately in the re-

spective passages, of a carburetor having corresponding air outlet passages of less capacity, cross connected in their inlet end portions to permit delivery of air from either carburetor passage to either engine inlet passage, and means for feeding liquid fuel into said cross connection.

9. A carburetor for internal combustion en-

gines, comprising the combination of an air supply tube, an oscillatory throttle valve having a port partially subdivided by a partition in line with the tube axis, a nozzle having its outlet at the outlet side of the throttle valve in line with said partition and spaced therefrom, and connections for supplying liquid fuel to the nozzle.

WARREN C. CONOVER.
